CLAIM

The ornamental design for a telescopic handle grabbing tool, as shown and described.

DESCRIPTION

FIG. 1 is a first perspective view of a telescopic handle grabbing tool showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the telescopic handle grabbing tool thereof;

FIG. 10 is an enlarged view of the selected portion in FIG. 1;

FIG. 11 is an enlarged view of the selected portion in FIG. 1; and,

FIG. 12 is an enlarged view of the selected portion in FIG. 1.

The broken lines shown in the drawings depict portions of the telescopic handle grabbing tool in which the design is embodied that form no part of the claimed design. The dot-dash broken lines depict enlarged portions that form no part of the claimed design.

1 Claim, 12 Drawing Sheets
